UNITED STATES PATENT OFFICE.

CHARLES V. FERGUSON, OF SCHENECTADY, NEW YORK, ASSIGNOR TO GENERAL ELECTRIC COMPANY, A CORPORATION OF NEW YORK.

ELECTRIC-ARC DEVICE.

Application filed December 3, 1918, Serial No. 265,086. Renewed March 13, 1924.

To all whom it may concern:

Be it known that I, CHARLES V. FERGUSON, a citizen of the United States, residing at Schenectady, county of Schenectady, State of New York, have invented certain new and useful Improvements in Electric-Arc Devices, of which the following is a specification.

My present invention relates to electrical discharge devices having a cathode operating at incandescence in an atmosphere of gas. It is the object of my invention to improve the efficiency and rectifying properties of incandescent cathode devices.

My invention comprises a method of operating a thermionic discharge of arc-like character in the vapor of an alkali metal and a device of the described class having an anode consisting of an alloy of alkali metal, the device being constructed to permit vaporization of said alkali metal by the electric discharge.

The accompanying drawing illustrates an embodiment of my invention.

The drawing shows a device comprising a sealed envelope 1 consisting of hard glass, quartz, or other material which is chemically inert to heated alkali metal vapor. It may be either evacuated or may contain a gas such as hydrogen, or argon, at suitable pressure, for example 4 or 5 centimeters of mercury pressure. The cathode 2 consists of a filament of refractory metal, such, for example, as tungsten. It is supplied with heating current by the leading-in conductors 3, 4, which may also consist of tungsten, and are sealed as usual into a stem 5. The anode 6 consists in part at least of an alkali metal, for example, an alloy of sodium and potassium, the proportions of which may be varied. I have used with good success an alloy containing one part by weight of sodium and two parts by weight of potassium. As shown in the drawing a sufficient amount of alkali metal is present to permit of the operation of a discharge from the cathode in the alkali metal vapor.

A device embodying my invention is particularly noteworthy for its low consumption of voltage, the discharge having the characteristics of an arc. For example, in a device in which the gap between cathode and anode

is about 1.0 cm. with a current of about one ampere, the observed potential drop is about one volt. The close proximity of the cathode and anode causes the discharge path to be wholly enveloped by alkali metal vapor which is evolved from the anode by the heat of the discharge, thus utilizing advantageously the low ionizing potential of alkali metal vapor.

A tube embodying my invention is particularly applicable as a rectifier for automobile and other small storage batteries as well as for attachment to direct current voltmeters to enable them to operate on alternating current.

What I claim as new and desire to secure by Letters Patent of the United States, is,—

1. An electric discharge device comprising a sealed container, cooperating electrodes one of which is constituted by a filament of refractory material and a quantity of alkali metal located in said container so close to said electrode that when said material is vaporized during operation sufficient vapor is provided to wholly envelope the discharge path between said electrodes at a pressure at which an arc-like discharge may be conducted therethrough at potentials approximating one volt.

2. An electric rectifying device comprising the combination of a sealed container, electrodes therein including a filamentary cathode consisting of refractory metal and an anode constituted by a body of alkali metal located so closely adjacent said cathode that by the vaporization of said metal sufficient vapor is produced to permit of the operation of an arc-like discharge therein with a voltage drop of the order of one volt for a current of about one ampere.

3. The method of operating an arc-like discharge between closely adjacent cooperating electrodes one of which emits electrons when heated which consists in supplying to the discharge path between said electrode the vapor of an alkali metal at a sufficiently high pressure to cause a discharge of about one ampere current value to have a potential drop of about one volt.

In witness whereof, I have hereunto set my hand this 2nd day of December, 1918.

CHARLES V. FERGUSON.
